UNITED STATES PATENT OFFICE.

JOHN MLINAR, OF CLEVELAND, OHIO.

CUSPIDOR.

1,043,339.

Specification of Letters Patent. Patented Nov. 5, 1912.

Application filed May 8, 1912. Serial No. 695,953.

To all whom it may concern:

Be it known that I, JOHN MLINAR, citizen of Austria-Hungary, residing at Cleveland, in the county of Cuyahoga and State 5 of Ohio, have invented certain new and useful Improvements in Cuspidors, of which the following is a specification, reference being had to the accompanying drawings.

This invention relates to improvements in 10 cuspidors and has for its primary object to provide a device of this character of simple and novel construction whereby the liability of upsetting the cuspidor and discharging its contents is entirely eliminated.

Another object of the invention is to provide a cuspidor consisting of a hollow body, 15 an inner liquid receiving receptacle, and means for mounting the same in said body whereby the same will always retain its 20 normal position with relation to said body.

A still further object of the invention resides in a cuspidor of improved construction whereby the various parts may be easily and quickly assembled or separated so that 25 access can be had to the interior thereof for cleaning the liquid receptacle, thus conducting to thorough sanitation in articles of this character.

With the above and other objects in view, 30 the invention consists of the novel features of construction, combination and arrangement of parts hereinafter fully described and claimed, and illustrated in the accompanying drawings, in which—

Figure 1 is a vertical section of a cuspidor embodying the present invention; Fig. 35 2 is a top plan view thereof; Fig. 3 is a section taken on the line 3—3 of Fig. 1; and Fig. 4 is a view similar to Fig. 1, the inner 40 liquid receiving receptacle being shown in section.

Referring in detail to the drawing 5 designates an outer substantially spherical casting or body which is preferably formed of 45 sheet metal. The lower portion of the sides and the bottom of this body have soldered or otherwise secured thereto a solid metal weight member 6 which acts to normally maintain said body or casing in an upright 50 position. This weight member is provided with a flat face 7, the remaining face portion of said member being convex and gradually merging into and forming a continuation of the wall of the sheet metal body 5. The 55 upper end of this body is open, said open end being provided with a flared or shallow

funnel-shaped entrance mouth 8, the greatest diameter of which is preferably slightly greater than the diameter of the spherical body 5. The arms of a spider 9 are secured 60 at their outer ends to the edge of the flared mouth 8, said spider arms being radially extended from a central body plate in which a short staff 10 is secured, said staff extending in axial alinement with the body 5. 65

The outer casing or body member 5 of the cuspidor is formed in two sections, the upper section carrying the flared mouth 8 and the lower section having secured thereto the above mentioned weight member 6. The 70 upper and lower sections of the casing are provided at their opposed ends with internal and external screw threads respectively which are adapted to be co-engaged to removably secure the sections together. Upon 75 the inner wall of each of said sections an annular rib or shoulder 11 is formed or secured in any preferred manner, and when the sections are connected, these ribs are engaged with each other. The engaging 80 faces of said ribs are provided with recesses or grooves 12.

An annular ring 13 is arranged within the sectional body 5 and carries the pivot studs 14 which are fixed to said ring at diametrically opposite points and are adapted to be received in the grooves 12 of the abutting shoulders 11 on the body sections. This ring is disposed in a horizontal plane within the body when the parts are in their normal 90 positions and within the same the liquid receiving receptacle 15 is pivotally mounted, said receptacle carrying the pivot pins 16 which are disposed in openings at diametrically opposite points in the ring 13. The 95 pivot pins on the receptacle extend at right angles with relation to the pivot pins 14 of the annular member or ring 13, and support the receptacle 15 for pivotal movement with respect to said ring. This liquid receiving 100 receptacle is also provided with a lower weighted wall as indicated at 17, and has an inwardly extending inclined wall 18, the lower open end of which is disposed above the axis of said receptacle. This inclined 105 directing wall is of greater diameter at its point of connection to the peripheral wall of the receptacle than the diameter of the flared mouth 8 at its juncture with the wall of the body 5. 110

By means of the above described arrangement of parts, it will be readily seen that

owing to the manner of mounting the liquid receiving receptacle 15 within the sectional body, said receptacle will at all times maintain its normal position, and the cuspidor 5 may be tipped over upon its side without danger of evacuating the contents of the receptacle. The extended edge of the flared mouth 8 and the staff 9 render it impossible to completely upset or reverse the position 10 of the cuspidor so that any liquid which may find its way into the space between the body and the inner receptacle will not be spilled. When the cuspidor body is tilted so that the axis of the annular member or ring 13 is 15 obliquely disposed, the receptacle 15 still retains its normal position owing to the pivotal mounting of said receptacle in the member 13. When the cuspidor is tilted in a plane in line with the axis of the receptacle 15, the annular member 13 in which said receptacle is mounted will then turn or rotate with respect to the body 5. It will 20 thus be seen that in either direction of tilting movement of the cuspidor, the entrance mouth or opening of the receptacle 15 will 25 still be disposed above its rotative axis.

From the foregoing it is thought that the construction and operation of the invention will be fully understood. Owing to the sectional construction of the body 5, the parts 30 thereof may be readily assembled and thoroughly cleaned and the receptacle 15 removed and also cleaned. The receptacle is then replaced in position in the notches or

grooves in the rib of the lower body section 35 and the upper body section is then threaded into place upon the wall of said lower section. As the device consists of but few elements which are of simple form, it will be appreciated that the invention can be produced at small cost and is extremely strong, durable and efficient in practical use. 40

While I have shown and described the preferred construction and arrangement of the various parts, it will be understood that 45 the invention is susceptible of considerable modification without departing from the essential feature or sacrificing any of the advantages thereof.

Having thus described the invention what 50 is claimed is:—

In a device of the character described, the combination with a substantially spherical hollow body member, of a liquid receiving member pivotally mounted within said body member to maintain a normal position with respect to the body member, said body member having a flared entrance mouth, a spider secured to the edges of said mouth, and a central staff rigidly secured to said spider 60 to prevent the tilting movement of the body member to an inverse position.

In testimony whereof I hereunto affix my signature in the presence of two witnesses.

JOHN MLINAR.
